UNITED STATES PATENT OFFICE.

GEORGE L. McWILLEN, OF SMARTVILLE, CALIFORNIA.

WIRE-STRETCHER.

1.001.547.

Specification of Letters Patent. Patented Aug. 22, 1911.

Application filed March 14, 1911. Serial No. 614,293.

To all whom it may concern:

Be it known that I, GEORGE L. McMILLEN, a citizen of the United States, residing at Smartville, in the county of Yuba and State of California, have invented certain new and useful Improvements in Wire-Stretchers, of which the following is a specification, reference being had to the accompanying drawings.

10. This invention relates to improvements in portable wire stretchers and has for its object to provide an improved device for such purpose which shall possess superior advantages with respect to efficiency in use.

15 Another object is to produce a device of this character that can be used for pulling stumps, hoisting or any other similar uses, and will also possess advantages in points of efficiency, durability and inexpensive of manufacture and at the same time being simple in construction and operation.

With the foregoing and other objects in view the invention consists in the novel features of construction and in the combinations and arrangements of parts hereinafter described, pointed out in the claim and shown in the accompanying drawings in which,

Figure 1 is a view showing my invention in use as a wire stretcher. Fig. 2 is a top plan view.

Referring more particularly to the drawing 1 indicates the frame which is substantially U shape in form and continued at one end into a V shape portion 2. Mounted in 35 the outer ends of the frame is a rotatable drum 3 having ratchet wheels 4 formed integral therewith, the frame 1 being mounted on the drum outside of the wheels 4. A hand lever 5 is provided having its forks 6 mounted on the ends of the drum 3 at a point centrally thereof. Arranged in the forks 6 are the slots 7, said slots being adapted to receive the ends of the operating bar 8. The bar 8 is held in engagement with

45 the ratchet wheels by means of a coil spring 9 which is mounted on a rod 10, said rod having a hook 11 formed at one end and engaged in an eye bolt 12 secured in the bar 8, the other end of the rod protruding 50 through an opening 13 formed in the cross piece 14 which is secured in the upper end of the forks 6, said rod having a hand-hold 14' formed thereon to disengage the bar 8 from the ratchet wheels 4.

55 The frame 1 is provided with the longitudi-

dinal slots 15 adapted to receive the ends of sliding stop bar 16, said bar being held in engagement with the ratchet wheels 4 by means of a coil spring 17 mounted on the rod 18, said rod having a hook formed at 60 one end thereof and engaged in an eye bolt 19 secured in the bar 16, the other end of the rod 18 protruding through an opening 20 formed in a brace piece 21 secured in the end of the frame 1 and a hand-hold 16' 65 formed on the outer end of said rod to disengage the bar 16 from the ratchet wheels 4.

Formed on the periphery of the drum 3 are a number of spaced lugs 22 between which the links of the chain 23 engage, the lugs 22 are spaced at 23' so that the ends of the links will engage therein and will be released when the drum rotates far enough beyond the center. 70

The ends of the frame are brought together at the V shaped portion 2 and are secured by means of the rivets 25, the extreme ends being formed into a hook 26, and a chain 27 having one end engaged on the hook 26 and the other end passed around the post 28 and then engaged on the hook 26. 75 80

In operating the wire stretcher the end 2 is secured to any stationary object and the chain 23 is secured to the wire clamp 24, the hand lever 5 is then brought downwardly which will rotate the ratchet wheels 4 and drum 3 and will tighten the chain 23 which in turn will pull the clamp 24 forward and tend to stretch the wire. When the lever 5 is released the stop bar 16 will hold the ratchet wheels 4 against backward movement.

It will be obvious that various changes in the details of construction and in the proportions may be resorted to for successfully carrying the invention into practice without sacrificing any of the novel features or departing from the scope thereof. 95

I claim—

In a device of the character described, the combination of a U-shaped frame having a hook formed at one end thereof, said hook serving for engagement by a chain to connect the frame to a post, a rotatable drum 105 mounted in the other end of said frame, ratchet wheels formed integral with said drum and disposed at each end thereof, said frame having slots formed therein adjacent the drum, a spring pressed stop bar slidably 110

mounted in said slots and engaging said ratchet wheels to prevent the backward movement of the drum, a hand lever, forks formed integral therewith and secured to the ends of said drum, said forks having slots formed therein, a spring pressed operating bar slidably mounted therein, said bar being adapted to engage the ratchet wheels for rotating said drum, and a flexible ele-

ment connected to a movable object and to adapted to be wound on the drum.

In testimony whereof I hereunto affix my signature in the presence of two witnesses.

GEORGE L. McMILLEN.
